UNITED STATES PATENT OFFICE.

EUGEAN BLAIR, OF LOUISVILLE, KENTUCKY.

BATTEN GRIP.

Application filed December 17, 1923. Serial No. 681,240.

To all whom it may concern:

Be it known that I, EUGEAN BLAIR, a citizen of the United States, residing at Louisville, in the county of Jefferson and State 5 of Kentucky, have invented new and useful Improvements in Batten Grips, of which the following is a specification.

This invention relates to batten grips adapted to be used upon barrels and boxes 10 or similar containers for holding the sides and ends in position with relation to each other and it consists in the novel features hereinafter described and claimed.

An object of the invention is to provide 15 a grip of simple and durable structure adapted to be applied to the ends of the batten strips whereby the said strips may be securely fastened to the container and when removed may be used repeatedly there- 20 by economizing in the material and use of the same which constitutes the retainer.

With this object in view the grip comprises a member having a plate portion adapted to be attached to the side of the 25 batten strip and a head portion adapted to pass over the upper edge of the side of the container. A clamping member is mov- 30 ably mounted in the head portion and adapted to cooperate with one side thereof for gripping the side portion of the container. A lug is mounted upon the plate portion and a shaft is screw threaded in the lug and passes through the inner side 35 of the head and is connected with the said clamping plate. By adjusting the shaft, which may be accomplished by rotat- 40 ing the same, the said clamping plate may be moved toward or away from the outer portion of the head. The lug is provided 45 with an opening and the shaft is provided with an opening and through these openings a sealing device or member may be passed to lock or restrain the shaft against turning movement after the parts have been proper- ly adjusted.

In the accompanying drawing:—

Figure 1 is a top plan view of a batten strip with the grip members applied.

Figure 2 is an edge elevation of the same.

Figure 3 is a sectional view taken on line 3—3 of Figure 2.

As illustrated in the accompanying drawing, the batten strip 1 is of usual configura- 55 tion and may be a part of the head of a barrel or may be a cross strip used upon a

box or similar container. Grip members are positioned at the ends of the batten strips and as these members are of light design and configuration a description of one will suffice.

Each grip member comprises a plate portion 2 which is attached to the upper surface of the batten strip 1 by means of screws 3 or similar securing devices. Each grip member is provided with a head portion 4 which is substantially U-shaped in transverse section. This portion 4 is adapted to rest over the upper ends of barrel staves when the device is applied to a barrel or over the upper edge of the side of a box 70 when the device is used upon a box structure. The outer side of the head 4 is provided at its lower edge with inwardly disposed teeth 5 which are adapted to enter the outer surface of the container to which 75 the device is applied. A lug 6 provided upon the plate portion 2 and the said lug is provided at its base portion with an opening 7.

A shaft 8 passes through the inner side 80 of the head portion 4 and is threaded in the upper portion of the lug 6. The inner end of the shaft 8 is squared as at 9 whereby a wrench may be used upon the shaft for turning the same. A clamping 85 plate 10 is located under the intermediate portion of the head 4 and the outer end of the shaft 8 is journaled in the plate 10. The shaft 8 is restrained against longitudinal movement transversely through the plate 90 10. Therefore when the shaft 8 is moved longitudinally the plate 8 moves with the shaft toward or away from the outer side of the head 4 but the plate 10 is restrained against turning movement. The shaft 9 95 is provided at a point between the inner side of the head 4 and the lug 6 with an opening 11. A sealing strip (not shown) may be passed through the openings 7 and 11 and its ends may be secured by any suitable means whereby the shaft 8 after being 100 adjusted cannot be tampered with or rotated.

In tractors the batten strip is disposed 105 transversely across the top of the container or receptacle and the heads 4 are engaged over the sides thereof. The shafts 8 are then turned whereby the side portions of the container are gripped between the clamping plates 10 and the teeth 5 at the 110

outer sides of the head. The sealing devices are then passed through the openings 7 and 11. Thus the parts are securely held together. To remove the batten strip the 5 sealing devices are cut or broken and the shafts 8 are rotated whereby the clamping plates 10 are carried away from the inner surfaces of the sides of the container therefore the said sides are released and the 10 batten strip 1 together with the gripping devices may be lifted off of the receptacle or container. Hence it will be seen that during the application of and the removal thereof of the batten strip to and from the receptacle the said strips are not damaged or 15 injured and consequently they may be reused any number of times. This will affect considerable saving in material and time and labor.

20 Having thus described the invention what is claimed is:—

1. A grip adapted to be used upon a batten strip comprising a member having a plate portion and a head portion, a lug 25 provided upon the plate portion, a shaft having screw thread engagement with the

lug and passing through the side of the head and a plate journaled upon the shaft.

2. A grip adapted to be used upon a batten strip comprising a member having 30 a plate portion, a lug located on the plate portion and provided with an opening, a shaft having screw thread engagement with the lug and passing through the side of the head, said shaft being provided with an 35 opening and a plate journaled upon the shaft.

2. A grip adapted to be used upon a batten strip comprising a member having 40 a plate portion, a lug mounted on the plate portion, said member having a head portion which is approximately U-shaped in transverse section and provided at its outer side with inwardly disposed teeth, a shaft journaled in the inner side of the head and having screw thread engagement with the lugs and a plate journaled upon the outer end of the shaft and located under the intermediate portion of the head.

In testimony whereof I affix my signature. 50

EUGEAN BLAIR.
